UNITED STATES PATENT OFFICE.

HERBERT S. MILLS, OF OAK PARK, ILLINOIS, ASSIGNOR TO MILLS NOVELTY COMPANY, OF CHICAGO, ILLINOIS, A CORPORATION OF ILLINOIS.

ELECTRICAL MUSICAL INSTRUMENT.

Application filed March 31, 1924. Serial No. 703,174.

This invention relates particularly to key-controlled means for controlling the playing-circuit and the tremolo-circuit of electrically played stringed musical instruments 5 of the viol class.

The primary object is to provide simple, improved means, whereby, in the normal action of the keys of the key-manual with which the machine is equipped, the various 10 notes corresponding to the several keys will be sounded in the normal playing of the instrument; and, when it is desired to operate the tremolo, this can be accomplished by additional movement of the key beyond the 15 normal movement required for playing.

The invention is illustrated in its preferred embodiment in the accompanying drawing, in which—

Fig. 1 represents a broken vertical sectional view through a key-manual and its attendant parts; Fig. 2, an enlarged broken sectional view of a portion of the mechanism shown in Fig. 1 and showing the key in the position which it occupies when the 20 playing-circuit is closed; Fig. 3, a broken elevational view showing a lost-motion connection between a key and one of the springs associated therewith; Fig. 4, a view similar to Fig. 2, but showing both the playing-circuit and the tremolo-circuit closed; and Fig. 5, a broken elevational view showing the 25 slidable member of the lost-motion connection in a different position from that which it occupies in Fig. 3.

In the illustration given, A represents a supporting-member, which may constitute a part of the frame of a console; and B, a key-manual mounted thereon.

The keys are fulcrumed on a cross-bar 40 1, preferably of angular form, which is mounted on the support A. Each key comprises a bar or lever 2 and a finger-piece 2^a mounted on the front end of the lever. Each member 2, in the illustration given, is provided with a fulcrum-notch 3 which rests upon the upper edge of an upturned flange of the cross-bar. Fixedly mounted on the support A is a member 4 which is equipped with studs 5 and 6. A normally tensioned 45 spring 5^a serves to hold the key in the position shown in Fig. 1; and a supplemental spring 6^a which has one end connected with the stud 6 and the other end joined by a lost-motion connecting device 7

to the inner end of the key-lever, comes 55 into action at the end of the normal playing movement of the key, so that the tremolo circuit can only be closed by exerting more than the normal playing pressure upon the key.

The playing circuit is designated 8. This circuit is equipped with a jack 9 which comprises a pair of spaced spring-members 9^a and an insulation-member 9^b on which they are mounted.

The tremolo-circuit is designated 10, and this circuit is equipped with a contact 10^a. Mounted on the member 2, near its rear end, is a plug 11, which has a reduced portion extending through the member 2 and connected with the upper end of the spring 5^a. The member 11 serves as a contact member for the playing-circuit and is adapted to close the playing-circuit in the normal operation of sounding the notes on the strings 70 of the instrument. Mounted on the member 2, in front of the contact-plug 11, is a yielding tremolo-circuit contact 12, which co-acts with the contact 10^a to close the tremolo-circuit when the key is given an 75 extra movement, that is, a movement beyond the normal playing movement. Fig. 4 shows the position after the key has been moved a sufficient distance to close both circuits.

Upon the supporting-member A, posts 13 are mounted. These posts support a cross-bar 14 equipped with a strip of felt 15. The keys are normally held in the position shown in Fig. 1 by the springs 5^a. It will 90 be understood that the key-manual is equipped with keys corresponding to the various notes to be sounded upon any string of the stringed instrument, or stringed instruments of the machine.

The lost-motion connection 7, in the illustration given, comprises a slotted slidable clip 7^a and a stud, or screw, 7^b which projects from the inner end of the key-lever and engages the slotted clip. When the key is 95 in the position shown in Fig. 1, the spring 6^a does not function to resiliently resist the key against movement under the action of the finger. The spring 5^a, however, functions in the normal playing of the instrument; and in the additional movement of the key, when the tremolo-circuit is to be 100 closed, the spring 6^a functions to yielding-

ly resist the additional movement. The parts may be so arranged and proportioned that the spring 6^a will be brought under initial tension by the time the circuit 8 is closed, and thus tend to resist further movement of the key. Under extra effort in the pressing of the key, however, the spring 6^a, which now acts cumulatively with the spring 5^a yields to permit the additional movement, thus allowing the tremolo-circuit to be closed.

With the arrangement described, it is possible for the player to strike the keys with sufficient force to close the playing-circuits, without fear of, at the same time, closing the tremolo-circuit. At any time desired, however, the operator may strike the key with additional force, thus effecting the increased amplitude of movement and closing the tremolo-circuit.

In practice, the circuit 8 may control the application of the fingers and of the bow to the string, thus sounding the note, assuming the musical apparatus to be of the type where the bow is continuously driven and requires only to be depressed to bring it into contact with the string when the note is to be sounded. Thus, in the example given,

the circuit 8 may control the bow-depressing magnet and finger-magnet.

The tremolo-circuit 10 may control a tremolo device of any suitable construction and arrangement, where such device is adapted for electrical control.

The foregoing detailed description has been given for clearness of understanding only, and no unnecessary limitations should be understood therefrom, but the appended claim should be construed as broadly as permissible in view of the prior art.

What I regard as new, and desire to secure by Letters Patent, is:

In means of the character set forth, a fulcrumed key, a playing-circuit contact mounted on the inner end thereof and a tremolo-circuit contact mounted in front of said first-named contact, a co-acting contact for each circuit, a spring holding said key under normal tension for playing, and a second spring having one end connected with a stationary member and having the other end connected with said key, one of said connections being a slotted lost-motion connection.

HERBERT S. MILLS.
